UNITED STATES PATENT OFFICE.

JOHN G. BENTLEY, OF GLEN ROCK, NEW JERSEY.

QUILL.

Application filed December 7, 1923. Serial No. 679,166.

To all whom it may concern:

Be it known that I, JOHN G. BENTLEY, a citizen of the United States, and resident of Glen Rock, in the county of Bergen and 5 State of New Jersey, have invented a new and useful Improvement in Quills, of which the following is a specification.

This application is a continuation in part of the subject-matter contained in my prior 10 application #641,400, filed May 25, 1923, on which Patent #1,479,448 was issued Jan. 1, 1924. The claim in this application reads on Fig. 3 of the patent.

Where a metal filament, such as tinsel, 15 has been wound on a quill of ordinary circular form in cross section, it has been necessary to make a quill of very great diameter in comparison to the thickness of 20 wrappings of the filaments around it and it has been also necessary to only put a very thin layer of said wrappings around the quill. Otherwise when the wound quill was in use in the loom, owing to the nature of 25 the metal filament which is smooth, hard and also very heavy, the whole wound mass would have a tendency to slide off the end of the quill as the shuttle was thrown back and forth in the loom. Therefore, owing 30 to the relatively small amount of filling 35 which can be wound on a quill of this character in comparison with what is wound on a quill when using other materials, such as cotton, silk, etc. the production of the metal filled cloth was very slow and expensive, this being due to the vast number of 40 quills a weaver would have to put in his shuttles during a day, making it necessary to stop the loom every time a new quill was inserted into the shuttle.

45 The object of my invention is to produce a quill in which the metal filament winding will be made to cling to the quill, thus rendering it possible to wind to a far greater thickness than was possible heretofore, without danger of the windings shelling off the quill and also materially increasing the length of time that a quill will last when weaving in the loom and thus relatively increasing the production.

50 My invention more particularly includes a quill having one or more spiral grooves extending longitudinally along its winding portion to form a plurality of edges and concave sides, whereby the winding will 55 cling to the quill.

By my improvement I have found that the thickness of the wrappings on the quill can be more than double the diameter of the empty quill, the edge or edges caused by the irregular shape of the quill along 60 the winding portion thereof serving to grip the metal tightly and distinctly bend it. The metal filament between the edges is wound comparatively loose so that the outer 65 layers have a tendency to sink into the folds of the inner layers at these loose points, thus causing the interlocking of the layers and preventing the windings from shelling off the quill. This type of winding will not hinder the drawing off of the filament as 70 it is more or less stiff and has a tendency to unwind or spring away from the quill which causes it to form a wide arc around the quill so that it will not catch in any of the edges which would be the case if the 75 wrappings were of a different nature.

The taper or thickness of the quill is not materially important as the wrappings may be wound on and drawn off quills of greatly varying thicknesses and tapers. 80

The quill may also be made in many different forms in cross section. Several of these forms are illustrated in the accompanying drawings, in which—

Fig. 1 represents in side elevation a quill 85 rectangular in cross section having four spiral grooves extending longitudinally along its winding portion.

Fig. 2 represents a cross section taken in the plane of the line II—II of Fig. 1. 90

Fig. 3 represents in side elevation a quill triangular in cross section having three spiral grooves extending longitudinally along its winding portion.

Fig. 4 represents a cross section taken in the plane of the line IV—IV of Fig. 3. 95

Fig. 5 represents in side elevation a quill having one spiral groove extending longitudinally along its winding portion.

Fig. 6 represents a cross section taken in the plane of the line VI—VI of Fig. 5. 100

The winding portion of the quill is denoted by 1, the headed end by 2 and the non-headed end by 3. The contour of the wrapping is denoted in dotted lines by 4. 105

In Figs. 1 and 2, the four spiral grooves 5 extend longitudinally along the winding portion once around the same, producing the pronounced edges 6.

In Figs. 3 and 4 the three spiral grooves 110

7 extend longitudinally along the winding portion partway around the same, producing the pronounced edges 8.

In Figs. 5 and 6 the single spiral groove 9 extends longitudinally along the winding portion twice around the same, producing the pronounced edges 10.

In all of these forms the edges are provided along the winding portion of the quill for bending the metal filaments, leaving looser portions between the edges so as to permit the interlocking of the several layers of the windings and thus preventing the shelling off of the coils from the end of the quill and destroying the further usefulness thereof.

The provision of these edges also permit the traverse winding of an interlocked mass of the metal filament on the quill, the said mass having a substantial thickness between its ends as compared to the diameter of the quill in the corresponding cross sectional plane.

In all of these forms the grooves are left 25 hand spirals, the reverse of the usual spiral

winding, and this feature also causes the winding to more closely cling to the quill.

It is evident that the edges or corners formed along the winding portion of the quill may be sharp or blunt, as the case may be, and that the body of the quill when viewed in cross section may assume many different shapes between such edges or corners so long as the windings will be caused to interlock and permit a substantial thickness of material to be wound and retained on the quill, the same not being dependent upon the size of the diameter of the quill, the invention being as applicable to quills of small diameter as to quills of large diameter.

What I claim is:—

A quill of polygonal form in cross section along its winding portion, the sides being concave.

In testimony that I claim the foregoing as my invention, I have signed my name this fourth day of December, 1923.

JOHN G. BENTLEY.
